REED SWITCH ENVELOPE

Bernard Edward Shlesinger, Jr., 9411 MacKlin Court,
Alexandria, Va. 22309

Filed Jan. 28, 1971, Ser. No. 110,784

Term of patent 14 years

Int. Cl. D13—03

U.S. Cl. D26—13

Fig. 1

Fig. 2

Fig. 4

Fig. 3

Fig. 6

Fig. 7

Fig. 8

Fig. 9

Fig. 10

Fig. 11

Fig. 12

Fig. 13

Fig. 14

Fig. 15

Fig. 16

FIG. 1 is a top plan view of a reed switch envelope;
 FIG. 2 is a bottom plan view thereof;
 FIG. 3 is a right side elevational view thereof;
 FIG. 4 is a front elevational view thereof;
 FIG. 5 is a left side elevational view thereof;
 FIG. 6 is a top plan view of a modified form of the reed switch envelope described in FIG. 1 showing my new design;

FIG. 7 is a bottom plan view thereof;
 FIG. 8 is a front elevational view thereof;
 FIG. 9 is a left side elevational view thereof;

FIG. 10 is a top plan view of a modified form of the reed switch envelope described in FIG. 1 showing my new design;

FIG. 11 is a bottom plan view thereof;
 FIG. 12 is a right side elevational view thereof;
 FIG. 13 is a left side elevational view thereof;
 FIG. 14 is a top plan view of a modified form of the reed switch envelope described in FIG. 1 showing my new design;

FIG. 15 is a bottom plan view thereof; and
 FIG. 16 is a side elevational view thereof.
 The end view opposite to the front elevational view shown in FIG. 4 is a mirror image thereof.

The end view opposite to the front end view shown in FIG. 8 is identical thereto.
 All of the other side elevations are identical to the side elevational view shown in FIG. 16.

I claim:
 The ornamental design for a reed switch envelope, as shown and described.
